MOWER GUARD

Thomas J. Scarnato, Park Ridge, and Paul C. Gordon,
Riverside, Ill., assignors to International Harvester
Company, Chicago, Ill., a corporation of New Jersey

Continuation of design applications Ser. No. 73,451, Feb.
5, 1963 and 73,452, Feb. 5, 1963. This application
Aug. 2, 1963, Ser. No. 76,137

Term of patent 14 years

(Cl. D40—1)

FIG. 1

FIG. 2

FIG. 3

FIG. 4

FIG. 5

FIG. 6

FIG. 10

FIG. 11

FIG. 9

FIG. 7

FIG. 8

FIGURE 1 is a top plan view of a mower guard showing our new design;

FIGURE 2 is a rear view of the mower guard;

FIGURE 3 is a front view thereof;

FIGURE 4 is a side elevational view thereof;

FIGURE 5 is a sectional view taken substantially on the line 5—5 of FIGURE 1;

FIGURE 6 is a bottom view thereof;

FIGURE 7 is a top plan view of another embodiment of the mower guard of FIGURES 1 to 6;

FIGURE 8 is a bottom view thereof;

FIGURE 9 is a side elevational view thereof;

FIGURE 10 is a rear view thereof; and

FIGURE 11 is a front view thereof.

This application is a continuation of our copending ap-

plications, Serial Nos. D. 73,451 and D. 73,452, filed February 5, 1963, respectively, and now abandoned.

We claim:

The ornamental design for a mower guard, substantially as shown and described.
